Primary Examiner — Karen S Acker

(74) Attorney, Agent, or Firm — FisherBroyles, LLP;
Jason M. Pass(57) CLAIM

I claim the ornamental design for a fabric, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

FIG. 1 is a top plan view of a first embodiment of a fabric according to my design; and,

FIG. 2 is a top plan view of a second embodiment, thereof. The broken lines surrounding the drawings depict the boundaries of the claim and form no part thereof.
